UNITED STATES PATENT OFFICE.

PARKER DODGE, OF WASHINGTON, DISTRICT OF COLUMBIA, ASSIGNOR TO THE JOHNSON SERVICE CO., OF MILWAUKEE, WISCONSIN, A CORPORATION OF WISCONSIN.

THERMOSTAT AND SIMILAR CONTROL DEVICE.

1,397,407.

Specification of Letters Patent.

Patented Nov. 15, 1921.

Application filed May 13, 1920. Serial No. 381,200.

To all whom it may concern:

Be it known that I, PARKER DODGE, a citizen of the United States, residing at Washington, in the District of Columbia, have invented certain new and useful Improvements in Thermostats and Similar Control Devices, of which the following is a specification.

This invention relates to thermostats and similar control devices, and particularly to means for shifting the mechanism either manually or by a clock to bring it into active relation with either of two individually adjustable stops for determining the temperature maintained by the thermostat.

The invention is particularly applicable to so called "night and day" thermostats for domestic use, and offers in addition to simple inexpensive construction, certain practical operative advantages. The user can set the device manually to either night or day setting at any time without deranging the relation of the clock to the device. For example the device may be set for night temperature before the time for actuation by the clock, and the clock will automatically restore the day setting at the usual time in the morning. Either the night or the day adjustment may be changed at any time without any manipulation other than the turning of the corresponding graduated head. The user can never apply force to any of the delicate parts of the device, either in making adjustments or in shifting from night to day setting. The shifting mechanism indicates directly whether the device is set for night or for day.

The device may be designed to receive with only one minor change, either of two types of clock, one requiring to be wound daily and intended merely to shift the device from night to day setting in the early morning, and the other of the eight day variety designed to shift the thermostat back and forth night and morning. This detail permits the manufacture of two types of instruments, one relatively cheap and the other more expensive, both of which have many of their parts other than the clock in common. This feature leads to economy in

manufacture and permits the instruments to be changed from one type to another by the substitution of a different clock and shift rod.

In the accompanying drawings I illustrate an electric thermostat embodying the invention in the form including an eight-day clock.

In the drawings:

Figure 1 is a front elevation of the complete device;

Fig. 2 is a section on the line 2—2 of Fig. 3;

Fig. 3 is a section on the line 3—3 of Fig. 2;

Fig. 4 is a fragmentary front elevation of the device with the clock removed;

Fig. 5 is a plan view of the shift rod.

Fig. 6 is a front elevation of the shift rod.

Fig. 7 is a front elevation of the carrier arm.

Fig. 8 is a side elevation of the carrier arm, and

Fig. 9 is a view of the shift spring.

The wall frame includes a back plate 11 and a front plate 12 connected by the side members 13. The side members 13 have slots 14 for the circulation of air. The front plate has an annular rim 15 to position the clock 16, the rim 15 being formed with holes 17 to receive the spring detents 18, which hold the clock in place. The openings 19 and 20 are for convenience in assembling the device, the opening 19 giving access to the screw which holds the carrier arm and the opening 20 giving clearance for the shift spring retaining tube. The opening 21 is to receive the arbor of the clock which actuates the shift rod.

At the upper end of back plate 11 are two stop posts 22 which may be cast integrally with the base. Threaded in the left hand post is the high temperature or "day" stop screw 23 which has a graduated knob 24. Threaded in the right hand post is the low temperature or "night" stop screw 25 which has a graduated knob 26. The knobs may be made one white and the other black to indicate at a glance that they are night and day adjustments.

The post 27 carries pivoted on it in any usual manner, for example by a shouldered screw 28 the thermostat carrier arm 29. These parts are so adjusted by means of a 5 spring washer 30 that a slight frictional resistance is offered to the movement of the arm sufficient to keep the arm from wavering at the moment of shifting. The upper portion of arm 29 terminates in a head 31 10 which swings between the ends of stop screws 23 and 25. The lower end of arm 29 is forked and terminates in two rounded heads 32 which straddle a flat portion 33 of the shift-rod indicated generally by the numeral 15 34. The heads 32 work between two stops 35 and 36 on rod 34, which are so spaced apart as to allow the rod some lost motion with reference to the arm. The interengagement of the forked end of the arm with the 20 flats on the rod holds the rod against rotation.

The rod 34 has, to the left of stop 35, a yoke 37 with two offset teeth 38 and 39. At the extreme left end it terminates in a cylindrical portion 40 guided on the side 13 of the frame. The rod 34 has to the right of stop 36 a reversely tapered enlargement 41, shown as two truncated cones placed base to base. This enlargement coacts with an annular 30 coil spring 42 confined in a channel 43 in a tube 44 which surrounds the enlargement.

The tube 44 is flanged at 45 and is held by a plug 46 screwed into wall 13 of the frame. The plug 46 also has a central opening to 35 guide the right end portion 47 of the rod 34 and affords a simple means of assembling the parts.

The spring 42 and reversely tapered enlargement 41 form a convenient reversible 40 spring mechanism, a term which I use in the claims to define a mechanism, capable of exerting resilient pressure in reverse directions, according as it is shifted to one or the other of two different positions. The specific 45 device illustrated and many variations of it, involving changes in the forms of the reversely tapered enlargement, and of the contracting spring member, have been used for a wide range of purposes. I have illustrated 50 the simplest one known to me as typical of the class and contemplate substitutions of known equivalents.

The parts are so proportioned that when the projecting end of the rod 34 is forced 55 in, the spring 42 will first ride over the middle of enlargement 41. Stop 35 or 36 (as the case may be) will then pick up arm 29 and shift it until head 31 is arrested by the opposed stop. At this point the end of rod 60 34 will be completely housed so that pressure can no longer be applied to it. The wall frame thus serves as a guard to prevent the exertion of undue force upon the shift rod 34, or through the shift rod upon other parts 65 of the device. The provision of lost motion

between the rod and arm insures that the quick throw will work positively even with a small range of motion for head 31 between stops 23 and 25. The frictional restraint on arm 29 exerted by washer 30 prevents 70 wavering of the arm during the initial movement of rod 34. The opposite ends 40 and 47 bear legends to show whether the thermostat is set for night or day and may be made black and white, respectively, to give 75 a visual indication at a distance. The rod 34 thus serves as convenient manually operable means for shifting the thermostat by reversing the reversible spring mechanism.

The thermostat chosen for illustration is 80 a bimetallic bar 48, of familiar type carried on a stud 49 on arm 29. The thermostatic bar 48 has at its free end a contact 50 which swings between two adjustable contact screws 51 and 52 threaded in posts 53 and 54. The 85 posts 53 and 54 are insulated from the back plate 11 at 55, and respectively, constitute terminal connections for two circuits. The screw 58 on back plate 11 serves as a connection common to both these circuits. The 90 function of thermostat arm 48 is to close these circuits in alternation. This function, the modes of connecting the circuits and the details of the accessory and controlled apparatus are familiar to those skilled in this 95 art and hence are not illustrated.

The clock 16 includes an eight day movement and a secondary spring motor train controlled thereby. The arbor 56 which projects from the back of the clock is driven 100 by this secondary train and the clock releases this train twice in each 24 hours in such manner that arbor 56 turns through 180° and then comes to rest. It is desirable that the clock be capable of releasing the 105 secondary train at different hours in alternate twelve-hour periods, and that both times of release be capable of adjustment. Such clocks are known in the art and include various means for determining and adjusting 110 the time of release of the secondary train. Since the details of the clock are not a part of the present invention they are not described in detail.

The arbor 56 carries an arm 57 shown in 115 Fig. 2 in its normal position of rest. In this figure the thermostat is shown in its night setting. At the hour in the morning determined by the adjustment of the clock (say 6 a. m.) arbor 56 is released and turns 120 one half turn. Arm 57 strikes tooth 39 and shifts rod 34 to the right far enough to cause spring 42 to roll over the middle of enlargement 41. The spring 42 completes the shifting movement. In the following evening at the hour determined by the adjustment of the clock (say 10 p. m.) the arbor 56 is released for another half turn. Arm 125 57 strikes tooth 38 and shifts rod 34 to the left, spring 42 completing the movement as 130

before. The device thus operates automatically night and morning so long as the clock runs.

Since the arm 57 when at rest stands in a horizontal position the rod 34 may be shifted manually to change the setting from day to night or the reverse without overcoming any resistance except that of the reversible spring mechanism. It will be observed that if such a reversal be made before the time of automatic actuation by the clock the clock will function at the time set but will not shift the rod 34. Thus the clock automatically resumes the correct phase relation with the shifting mechanism.

This is an important advantage, because regardless of any manual shifting the clock can never operate to establish the night adjustment during the day, or the day adjustment during the night. The possibility of making, for example, the night adjustment at a time earlier than that automatically affected by the clock is a useful feature of the invention.

To provide a cheaper instrument using the same main parts I substitute for the rod 34 a rod lacking the tooth 38 but otherwise identical, and for the eight day clock I substitute a common alarm clock in which 56 is the alarm winding arbor. Arm 57 serves as the alarm winding key. At night the clock is wound and set, the rod 34 is manually shifted to the left and the clock put in position. In the morning the release 35 of the alarm train causes the winding arbor to turn, and this shifts rod 34 to the right, where it remains regardless of continued rotation of arbor 56. Because of the relative cheapness of alarm clocks such an embodiment of the invention is quite inexpensive.

The main inventive ideas are in the adjusting and shifting mechanisms and their relation to clock mechanisms to secure automatic shifting. Obviously these principles can be used with other adjustable automatic control devices, such for example, as hygrometers, and with devices functioning by the control of pneumatic as well as electric motive energy. Such substitutions are contemplated by me.

Thermostats and like devices are capable of adjustment in various different ways. For example, in electric thermostats, the 55 moving element may be shifted with reference to fixed contacts, or the contacts may be movable and the thermostat have a fixed support, or both thermostat and contacts may be capable of simultaneous adjustment. This is familiar to those skilled in the art. In all these cases the adjustment is dependent on the motion of some movable member. In the present case the arm 29 is such 60 movable member, and I use the term movable member in the claims in its generic

sense to define this part or its functional equivalent.

Having thus described my invention what I claim is:

1. The combination of an automatic control device including a responsive element; a movable member for adjusting the action of said element; stops serving to limit the movement of said member in opposite directions; a reversible spring mechanism serving to hold said member against each of said stops in alternation, as the action of the spring mechanism is reversed; and means for shifting said spring mechanism to reverse its action. 70 75

2. The combination of an automatic control device including a responsive element; a movable member for adjusting the action of said element; stops serving to limit the movement of said member in opposite directions; a reversible spring mechanism serving to hold said member against each of said stops in alternation, as the action of the spring mechanism is reversed; and manually operable means for shifting said spring mechanism alternately in reverse directions to reverse its action. 80 85

3. The combination of an automatic control device including a responsive element; a movable member for adjusting the action of said element; stops serving to limit the movement of said member in opposite directions; a reversible spring mechanism serving to hold said member against each of said stops in alternation, as the action of the spring mechanism is reversed; and time controlled means serving to shift said spring mechanism to reverse its action. 90 95 100

4. The combination of an automatic control device including a responsive element; a movable member for adjusting the action of said element; stops serving to limit the movement of said member in opposite directions; a reversible spring mechanism serving to hold said member against each of said stops in alternation, as the action of the spring mechanism is reversed; and time controlled means serving to shift said spring mechanism periodically back and forth to reverse its action repeatedly. 110 115

5. The combination of an automatic control device including a responsive element; a movable member for adjusting the action of said element; stops serving to limit the movement of said member in opposite directions; a reversible spring mechanism serving to hold said member against each of said stops in alternation, as the action of the spring mechanism is reversed; manually operable means for shifting said spring mechanism to reverse its action; and a movable clock-controlled member serving when actuated by the clock to engage and shift said manually operable means. 120 125

6. The combination of an automatic con- 130

- trol device including a responsive element; a movable member for adjusting the action of said element; stops serving to limit the movement of said member in opposite directions; a reversible spring mechanism; a lost motion connection between said spring mechanism and said movable member; and means for shifting said spring mechanism to reverse its action.
10. 7. The combination of an automatic control device including a responsive element; a movable member for adjusting the action of said element; stops serving to limit the movement of said member in opposite directions; a reversible spring mechanism; a lost motion connection between said spring mechanism and said movable member; manually operable means for shifting said spring mechanism; and a guard serving to limit the manual actuation of said spring mechanism to a portion of its range but sufficient to insure reversal of the action of the spring mechanism.
8. The combination of an automatic control device including a responsive element; a movable member for adjusting the action of said element; stops serving to limit the movement of said member in opposite directions; a reversible spring mechanism; a lost motion connection between said spring mechanism and said movable member; manually operable means for shifting said spring mechanism to reverse the same; a guard serving to limit the manual operation of said spring mechanism to a portion of its range of action
- less than the whole, but sufficient to insure reversal; and a movable clock controlled member normally at rest disengaged from said manually operable means and serving when actuated by the clock to engage and 40 shift the same.
9. The combination of an automatic control device including a responsive element; a movable member for adjusting the action of said element; individually adjustable stops 45 serving to limit the movement of said member in opposite directions; a reversible spring mechanism; a lost motion connection between said spring mechanism and said movable member; and means for shifting 50 said spring mechanism to reverse its action.
10. The combination of an automatic control device including a responsive element; a movable member for adjusting the action of said element; individually adjustable stops 55 serving to limit the movement of said member in opposite directions; a reversible spring mechanism; a lost motion connection between said spring mechanism and said movable member; manually operable means 60 for shifting said spring mechanism; and a guard serving to limit the manual actuation of said spring mechanism to a portion of its total range of motion sufficient to secure reversal of the spring mechanism but less 65 than said total range as defined by the closest setting of said adjustable stops.

In testimony whereof I have signed my name to this specification,

PARKER DODGE.
